CLAIM

The ornamental design for an optical media disc case, as shown and described.

DESCRIPTION

FIG. 1 is a perspective view in closed configuration of an optical media disc case showing my new design;

FIG. 2 is a top plan view in closed configuration thereof;

FIG. 3 is a bottom plan in open configuration view thereof;

FIG. 4 is a perspective view in open configuration thereof; and,

FIG. 5 is a top plan view in open configuration thereof.

The broken line showing of the disc case is included for the purpose of illustrating environment and forms no part of the claimed design.
